(57) **CLAIM**

The ornamental design for a pull-out sofa bed with track arm, as shown and described.

DESCRIPTION

FIG. 1 is a front view of the pull-out sofa bed with track arm in a first position;

FIG. 2 is a front perspective view of the pull-out sofa bed with track arm in the first position;

FIG. 3 is a front perspective view of the pull-out sofa bed with track arm in a second position;

FIG. 4 is a front perspective view of the pull-out sofa bed with track arm in a third position;

FIG. 5 is a front perspective view of the pull-out sofa bed with track arm in a fourth position;

FIG. 6 is a front perspective view of the pull-out sofa bed with track arm in a fifth position;

FIG. 7 is a front perspective view of the pull-out sofa bed with track arm in a sixth position;

FIG. 8 is a front perspective view of the pull-out sofa bed with track arm in a seventh position;

FIG. 9 is a left side view of the pull-out sofa bed with track arm in the third position;

FIG. 10 is a right side view of the pull-out sofa bed with track arm in the third position;

FIG. 11 is a left side view of the pull-out sofa bed with track arm in the fifth position; and,

FIG. 12 is a right side view of the pull-out sofa bed with track arm in the fifth position.

The broken lines showing in FIGS. 1-12 are to show portions of the pull-out sofa bed with track arm, which form no part of the claimed design.

1 Claim, 12 Drawing Sheets
